UNITED STATES PATENT OFFICE.

SPENCER HEATH, OF BALTIMORE, MARYLAND.

APPARATUS FOR MACHINING PROPELLER-BLADES.

1,373,813.

Specification of Letters Patent. Patented Apr. 5, 1921.

Application filed February 23, 1918. Serial No. 218,857.

To all whom it may concern:

Be it known that I, SPENCER HEATH, a citizen of the United States, residing at Baltimore, in the State of Maryland, have 5 invented new and useful Improvements in Apparatus for Machining Propeller-Blades, of which the following is a specification.

This invention relates to improved apparatus for machining and milling large helical surfaces such as those of propellers or 10 propeller blades.

One object of the invention is to provide a simple machine in which the movement of a cutter member follows substantially automatically the movement of a model follower 15 actuated by the contact of the same against the surface of a model.

Another feature of the invention is the design and mounting of the cutter members 20 and the model follower members on a pivoted frame balanced by means of an electric motor.

Another feature of the invention is the arrangement of the single control means for 25 adjusting the vertical and horizontal position of the cutter and model follower members.

Further objects of the invention will be described and claimed in the following 30 specification and claims and illustrated in the accompanying drawings in which,—

Figure 1 represents a side elevation partially in section, of an apparatus constructed according to my invention.

Fig. 1^a represents a fragmentary view 35 looking upward at the cutter carrying support and showing the cutter members carried thereby.

Fig. 1^b represents a fragmentary view 40 taken on the line 1^b—1^b of Fig. 1 showing the single control means.

Fig. 2 represents a plan view taken on the line 2—2 of Fig. 1, showing the means for reciprocating the primary carriage.

Fig. 3 represents a front view of the primary carriage showing the controlling means for the motor.

Fig. 4 is a sectional view taken on the line 4—4 of Fig. 1.

50 Referring in detail to the drawings, 1 represents the horizontal work support and 2 represents a similar horizontal model support located immediately below and parallel therewith. These supports 1 and 2 are held stationary and in a fixed relation to each other at their outer ends by suitable upright

supports, not shown. Mounted on tracks 3 below the supports 1 and 2 and parallel therewith is a primary carriage 4 provided with wheels 5 adapted to engage the tracks 3. 60 The wheels 5 are rigidly mounted on horizontal axles 6 journaled in the opposite vertical sides 7 and 7^a of the carriage 4. Rigidly fastened in any suitable manner to the flanges 8 and 8' respectively, of the sides 7 and 7^a, is a U shaped frame 9, having its upright sides 9^a extending horizontally and in the same direction with the axles 6. Mounted on top of the upright sides 9^a for movement parallel therewith is a secondary carriage 10 provided with triangular side members 11 extending parallel to the sides 9^a. The forward end of the secondary carriage 10 is supported on the sides 9^a by means of flanged wheels 12, constituting driven members, keyed on an axle 13 journaled in the sides 11 of the secondary carriage 10. The wheels 12 are provided with gear teeth 14 adapted to mesh with a rack, 14^a, fastened to the sides 9^a as clearly shown in Figs. 1 and 2. 75 The rearward end of the secondary carriage 10 is slidably supported on the sides 9^a by means of plates 15 fastened to the secondary carriage 10. The plates 15 are provided with grooves 16 (see Fig. 4) slidably engaging tongues 17 fastened to the sides 9^a. These plates 15 serve to slidably anchor the carriage 10 to the sides 9^a. The frame on which the cutter tools and model followers are carried consists of a lower model support 18 journaled at one end to the axle 13 together with an upper tool support 19 journaled on a rod 20 which is carried by the sides 11 of the secondary carriage 10 directly above the axle 13. The tool support 19 is maintained in a constant parallel position with the model support 18 by means of a link 21 connecting their outer ends. Journaled to the support 19 above the stationary supports 1 and 2 is a horizontal axle 22 having keyed to its ends the rotary cutters 23 and 23^a. Carried by the support 18 directly below the axle 22 is a horizontal axle 24 carrying at either end thereof the rotatably circular wheels 25 and 25^a. These 90 wheels 25 and 25^a are hereinafter termed model followers and are adapted to slide or roll on the surface of the form serving as a model and denoted by the reference numeral 2^a, mounted upon the support 2. The 100 work 1^a which is to be formed into a propeller blade by means of the cutter 23 is 110

fastened to the upper surface of the support 1 by suitable supports or clamps indicated diagrammatically at 1^b. Mounted rigidly on the rear end of the support 19 is an electric motor 26 for rotating the cutters 23 and 23^a. A belt 27 connects the motor 26 to a pulley 28 keyed to the shaft 22. The motor 26 also acts to maintain the supports 18 and 19 in a balanced position. Directly beneath the motor 26 is a screw-threaded rod 29 journaled in bearings 30 carried by the support 19. On the rod 29 is an auxiliary balancing weight 31 adjustable lengthwise thereon by means of the hand wheel 32.

15 The movement of the secondary or upper carriage 10 forwardly or rearwardly is controlled by means of a hand wheel 33, carried by the forward end of the support 18. The wheel 33 is keyed at one end to a horizontal axle 34 having a sprocket wheel 35, constituting a drive member, keyed to its other end. The sprocket wheel 35 is connected to a larger driven sprocket wheel 36, keyed to the axle 13, by means of a chain 37. Thus 20 by rotating the hand wheel 33 in either direction a corresponding movement is imparted to the flanged wheels 12 causing a horizontal movement of the secondary carriage 10. By a downward or upward pressure 25 on the hand wheel 33, the cutter members 23, 23^a and the model followers 25, 25^a are brought into and out of engagement, respectively, with the work 1^a and the model 2^a. This is made possible because of the pivotally balanced frame members 18 and 19 adapted to move together. The rapidity with which the cut is made by the rotary cutters 23, 23^a can be varied according to the 30 degree of pressure brought to bear on the hand wheel 33.

40 The lower or primary carriage 4 is moved uninterruptedly along the tracks 3, and transversely to the adjustment movement of the upper or secondary carriage, by the power supplied from the electric motor 38 mounted on the carriage 4. Mounted on the inner side 7 of the carriage 4 and adapted to turn freely is a long pulley 39. On the opposite side 7^a is a shaft 40 having at its ends 45 the worm gears 41 adapted to engage corresponding gears 42 mounted rigidly with the axle 6 of the lower carriage 4. On the shaft 40 between the work gears 41 and immediately opposite the pulley 39 is a drive pulley 43 and a loose pulley 44 and a similar pulley 45 on either side thereof. The pulley 43 is rigidly fastened to the shaft 40 and adapted to turn therewith. A drive belt 46 extends from the motor 38 to the pulley 39 50 near the center of the latter. Extending from the pulley 39 on one side of the belt 46 is a straight belt 47 extending to the loose pulley 45, and on the other side is a crossed belt 48 extending from the pulley 39 to the loose pulley 44. At the front of the entire appa-

ratus adjacent the hand wheel 33 is a handle 49 acting as a lever to rock the shaft 50 supported on the carriage 4. The shaft 50 is connected to a belt shifting rod 51 suitably supported by a rod 52 (see Fig. 3). Fas- 70 tened to the shifting rod 51 are the belt en-gaging members 53 and 54. It will be ob-served that when the belt 47 is moved to the pulley 43 it will be driven counterclockwise. Conversely, when the belt 48 is moved to the 75 pulley 43 it will be driven in a clockwise direction. The speed of travel of the car-riage 4 along the tracks 3 will depend upon the ratio of pulleys and worm gearing. The control of the belts and application of 80 power may be regulated at will by the hand lever 49. Mounted on the front of the hori-zontal support 2 and projecting horizontally forward from the same is a pin 55 inserted into one of a series of openings. This pin 85 is adapted to engage with a rod 56 which is also connected to the shaft 50. Endwise movement of the carriage 4 will bring the rod 56 into engagement with the pin 55 thus shifting the belts and reversing the applica-tion of power and the movement of the car-riage.

The hand lever 49 is normally held in a vertical inoperative position by means of rollers 57 engaging a spring member 58 (see 95 Figs. 1 and 3). The rollers 57 are carried by a suitable support 59 fastened to the shaft 50. A rod 60 fastened to the shaft 50 is connected to a knife switch 61 by means of a link 62. This switch is in circuit with the 100 electric motor 38 and is open when the hand lever 49 is in its normal inoperative position.

The operation of the structure will be understood from the foregoing description of the construction when considered with 105 the following explanation. The model sur-face or form to be followed is indicated at 2^a. It will be observed that the structure provides a surface considerably broader than the surface of the work which is indi-cated at 1^a. This is arranged in this manner so that the model follower wheel 25 or 25^a would not slip off the edge of the structure and allow the cutter members to cause any 110 damage by suddenly dropping off the work 115 1^a. In operating the machine the operator would grasp the lever 49 in one hand and the wheel 33 in the other hand. By oscillat-ing the lever 49 the cutter members are re-ciprocated in continuous movement longitu-dinally of the work. By rotating the wheel 120 26 alternately in both directions the cutter members are moved for adjustment trans-versely of the work, and by exerting an up-ward or downward pressure on the wheel 33 125 the cutters can be placed into or out of cutting engagement with the work. The rapid-ity with which the cut is made can be regu-lated by the degree of downward pressure 130 exerted on the hand wheel 33. It will thus

be observed that by this arrangement any desired cutting movement can be given the cutters at will by the manipulation of the lever 40 and the wheel 26. In the operation 5 of this machine the continuous lengthwise movement of the power driven primary carriage and cutter member provides for stroke or travel, and accordingly the adjustment is at right angles to the path of power driven 10 travel and is entirely hand controlled. Stroke or travel makes the cut, and adjustment normally takes place between cuts and, therefore, differs from stroke or travel.

From the foregoing it will be clear that 15 this invention provides a machine which is simple in construction and easy to operate. The invention includes the use of equivalent methods of actuating the control means and such changes are contemplated within 20 the scope of the invention. While I have shown and described my invention as being used in machining and milling propeller blades, it is to be understood that it may be used for shaping articles other than propellers, such as struts.

What I claim is:

1. In an apparatus for machining propeller blades comprising a stationary model support, a stationary work support parallel thereto, a power driven primary carriage mounted to travel within a predetermined distance and substantially parallel to said work support and to effect a continuous cutting movement lengthwise of the work, 30 means to move said primary carriage in said continuous travel lengthwise of the work, a secondary carriage mounted to be adjusted transversely on said primary carriage and substantially at right angles to the line of movement of said primary carriage for each successive cutting position, a tool carrying frame pivotally mounted on said secondary carriage, a model follower member mounted on said frame, a cutter member mounted on 35 said frame and at a constant distance from said model follower member, and a common manually operated control member carried by said frame for reciprocating said secondary carriage and rocking said frame.
2. In an apparatus for machining propeller blades comprising a stationary model support, a stationary work support parallel thereto, a power driven primary carriage mounted to travel parallel to said supports 50 during the cutting action to effect a continuous cutting movement lengthwise of the work, means to move said primary carriage in said continuous travel lengthwise of the work, a secondary carriage mounted on said primary carriage capable of manual adjustment transversely to said supports, and substantially at right angles to the line of movement of said primary carriage for each successive cutting position, a frame pivoted to 55

said secondary carriage and extending forwardly and rearwardly of said pivotal support, a model follower member and a cutter member mounted in fixed relation to each other at the forward end of said frame, actuating means for rocking said frame, and 65 operating means for said cutter member mounted at the rearward end of said frame whereby the frame is maintained in a balanced position.

3. In an apparatus of the class described, 70 a stationary model support, a stationary work support parallel thereto, a power driven primary carriage to effect a cutting movement lengthwise of the work, a secondary carriage mounted to be adjusted transversely on said primary carriage and substantially at right angles to the line of movement of said primary carriage for each successive cutting position, a cutter supporting arm pivotally mounted on said secondary carriage 75 and extending on either side of the pivotal point, a model follower arm pivotally mounted on said secondary carriage parallel to said cutter supporting arm, a link connecting said arms, a model follower 80 member carried by said model follower supporting arm, a cutter member carried by said cutter supporting arm on one side of the pivotal point, a motor for said cutter carried by said cutter supporting arm on the 85 opposite side of the pivotal point from said cutter member, an auxiliary adjustable weight carried by said cutter supporting arm whereby said arms are maintained in a balanced or unbalanced position, and a control member for moving said cutter supporting arm and said model follower arm up 90 and down and laterally.

4. In an apparatus of the class described, 95 a stationary model support, a stationary work support parallel thereto, a primary carriage mounted to travel within a predetermined distance and substantially parallel to said work support and to effect a continuous cutting movement lengthwise of the 100 work, means to move said primary carriage in said continuous travel lengthwise of the work, a secondary carriage mounted to be adjusted transversely on said primary carriage and substantially at right angles to 105 the line of movement of said primary carriage for each successive cutting position, a cutter member, a model follower member, a frame pivoted to said secondary carriage having said cutter member and said model 110 follower member mounted thereon in a fixed relation to each other, means for balancing said frame, and a unitary controlling means for adjusting said secondary carriage transversely and oscillating said frame, said 115 unitary controlling means consisting of a driving member carried by said frame, a driven member carried by said secondary 120 carriage.

carriage and engaging said primary carriage, and a driving connection between said driving and driven members.

5. In an apparatus for machining propeller blade comprising a stationary model support, a stationary work support parallel thereto, a power driven primary carriage mounted to travel parallel to said supports during the cutting action and to effect a cutting movement lengthwise of the work, a secondary carriage mounted on said primary carriage and capable of adjustment transversely to said supports and substantially at right angles to the line of movement of said primary carriage for each successive cutting

position, a frame pivoted to said secondary carriage extending forwardly and rearwardly of said pivotal support, a model follower member and a cutter member mounted in fixed relation to each other at the forward 20 end of said frame, manually operated actuating means for said frame, and operating means for said cutter member mounted at the rearward end of said frame whereby the frame is maintained in a balanced position. 25

In testimony whereof I have hereunto set my hand.

SPENCER HEATH.
